[57] CLAIM

The ornamental design for a safety wand for bicycles or
the like, as shown and described.

DESCRIPTION

FIG. 1 is an exploded front elevational view of a safety
wand for bicycles or the like showing my new design,
with the holding elements shown separated for clarity
of illustration only;

FIG. 2 is an exploded rear elevational view thereof;

FIG. 3 is an enlarged exploded left side elevational view
thereof;

FIG. 4 is an enlarged exploded right side elevational
view thereof;

FIG. 5 is an exploded top plan view thereof; and,

FIG. 6 is an exploded bottom plan view thereof.

FIG. 1

FIG. 2

*FIG. 3**FIG. 4*FIG. 5

FIG. 6
